(57) **CLAIM**

The ornamental design for a mobile adapted to display multiple photographs vertically and/or horizontally off a metal arc armature, as shown and described.

DESCRIPTION

FIG. 1 is a perspective view of a mobile adapted to display multiple photographs vertically and/or horizontally off a metal arc armature showing my new design; and, FIG. 2 is a perspective view showing an alternative embodiment of my new design.

Claimed is a design for a mobile adapted to display multiple photographs vertically and/or horizontally off a metal arc armature comprising two interchangeable portions: one or more mobile portions, an arc armature portion and supporting structure portion.
